PRESERVING CAN

Heinrich Karl, Jersey City, N. J.

Application July 23, 1932, Serial No. 624,219

2 Claims. (Cl. 220—66)

This invention relates to improvements in receptacles and has particular reference to metallic cans which are hermetically sealed and used to contain and preserve foodstuffs or the like.

Heretofore, it has been customary to attach the lid of a can to the body thereof by a simple joint which is soldered or otherwise sealed, and to open the can to dispense its contents by penetrating the lid with the blade of a suitable opener utilized to cut the lid. The insertion of the blade through the lid and into the interior of the can, and subsequent cutting operation, has been known to cause small particles of metal to fall into the contents of said can with the consequent danger to the health of consumers of said contents.

In my copending application filed March 6, 1931, Serial Number 520,614, there is described a construction of can designed to overcome the above difficulty by the provision of a novel form of joint between the can body and lid which provides an annular space extending exteriorly about the said body and adapted to be penetrated by the blade of an opener. As a consequence of the formation of this space, said blade will not extend into the interior of the can body and hence no particles of metal will fall into the contents of the can. The joint referred to is made by bending the end of the can body to form an annular groove into which is inserted and sealed a flange on the lid of the can, said flange combining with the can body to provide the space into which the opening tool is inserted. However, it has been found with this construction that, owing to the formation of the joint which connects the can body and lid and the location of the annular space extending about said joint, the required amount of pressure necessary to effectively seal the flange of the lid in the groove formed at the end of the can body cannot be applied to the parts without deforming the portion of the flange of the lid which constitutes a wall of said space, and consequently destroying the latter for the aforesaid purpose.

In accordance with the present invention it is proposed to avoid the above-mentioned objectionable feature by assembling the upper end of the can body and the lid therefor in such manner that adequate pressure in opposite directions may be exerted upon the joint between said elements by means of chucks or the like to effectively seal said joint without altering the contour of the space which is disposed exteriorly of the can body and into which an opener is adapted to be inserted when cutting the lid.

Another feature of the invention is to provide

an improved joint between the can body and lid therefor in which the former, adjacent one end, is folded upon itself to constitute a constricted open end, the periphery of which is formed by the fold in the material so that a finished edge is presented instead of the raw edge of the material at the extremity of the body.

The inventive idea involved is capable of receiving a variety of expressions some of which, for the purposes of illustration, are shown in the accompanying drawings wherein:

Figure 1 is a perspective view partly in section of a can constructed in accordance with the invention.

Figure 2 is a fragmentary vertical sectional view showing the joint between the can body and lid therefor, as illustrated in Figure 1.

Figure 3 is a view similar to Figure 2 illustrating slightly different forms of the lid and bottom of the can.

Figure 4 is a fragmentary side elevation of another form of can in which the body and lid are of the same diameter.

Figure 5 is a fragmentary vertical section of the joint for the can body and lid illustrated in Figure 4, and showing the manner in which a tool such as a pair of pliers may be utilized to remove the lid.

Figure 6 is a fragmentary sectional view showing another form of bottom for the can.

Figure 7 is a fragmentary perspective view showing still another form of the invention.

Figure 8 is a vertical sectional view through the joint for the body and lid illustrated in Figure 7, and

Figures 9 and 10 are fragmentary sectional views of two other different forms of joints.

The material used in the construction of the various forms of the can may be of any desired kind such as customarily employed in receptacles of this character, and that of the can body 11 is rolled to cylindrical form according to the usual methods although it is to be understood that the invention is not to be considered as restricted to this particular shape of body. In Figure 1 the bottom 12 of the can is shown as being of concavo-convex formation with the periphery thereof flanged to interlock with the lower end of the body 11 to constitute a joint 13 of the usual construction. The bottom 14 shown in Figure 3 is likewise joined to the can body and inwardly of its periphery is curved in different directions as shown. In Figure 6 the major portion of the bottom 15 is also curved. The purpose of making the various bottoms 12, 14 and 15 curved is to

render it difficult to force the blade of a can opener though the same and thus minimize the possibility of a person cutting the bottom of the can to open it instead of removing the lid.

- 5 In Figure 2 the upper end of the body 11 is bent inwardly and upwardly and then folded upon itself to form superposed layers of material 16 which constitute a groove the purpose of which will appear in the course of the description. By 10 so bending and folding the material of the body 11 a constricted open end for said body is provided the periphery of which is formed by the fold in the material to provide a finished edge 17 for said open end as distinguished from the raw 15 edge of the extremity of the can body which would form said opening if the material were not folded upon itself. When assembling the body 11 and the lid 18 therefor, the groove made by the superposed layers 16 has first introduced into the 20 same a packing or binder 19 of any desired nature which will act to hermetically seal the can when the lid is in place. The lid 18 is curved somewhat like the bottom 12 and adjacent its outer edge is stamped to provide an annular channel 20 the 25 walls of which are angularly disposed, this channel acting as a guide when utilizing a can opener to cut the lid. The peripheral portion of the lid 18 exterior of the channel 20 is bent to provide a flange 21 having an angularly disposed in- 30 turned portion 22 which is adapted to be inserted into the groove formed by the layers 16, the placing of said portion 22 in the groove being subsequent to the insertion of the packing 19 therein. When the lid has been so placed the de- 35 pending portion of the flange 21 thereof combines with the adjacent section of the portion 22 and with the outer inclined wall of the channel 20 to form an annular space 23 which extends circumferentially around and exteriorly of the open 40 end of the can body formed by the fold 17 so that when the blade of an opener is made to penetrate the lid at the bottom of the channel 20 it will enter said space. In this manner any small particles of metal which may be broken 45 from the lid in the cutting operation will fall into said space instead of entering the body of the can as occurs when the ordinary type of can is opened. By the formation of the superposed layers 16 and the insertion of the portion 22 of 50 the flange 21 into the groove formed by said layers it will be obvious that at least one thickness of material will be interposed between the bottom of the channel where the blade of the opener enters and the wall of the can body. This ad- 55ditional thickness or layer of the material will avoid the possibility of the blade of the opener penetrating through the wall of the can body in the event that excessive pressure should be applied to said blade when forcing it through the 60 lid 18.

In the form of the invention being described the lid is sealed in place on the can body before the foodstuffs or other materials are placed in the latter and after this has been done the bottom of 65 the can is sealed in the usual manner. When securing the lid in place the formation of the adjacent end of the body and the lid is such that an inner chuck may be inserted into the interior of the body and engaged with the adjacent layer 70 16 of the folded material of the body and an outer chuck engaged with the lid including the inner wall of the channel 20. Then pressure upon the chucks in opposite directions and against the parts of the can which they engage will com- 75 press the layers 16 and tightly bind the same

against the portion 22 so that the packing in the groove formed by said layers will tightly seal the lid in place.

If desired, before the lid 18 is mounted in position, a quantity of any suitable adhesive 24 may be placed in the annular space 23 so that any particles of the matter broken away from the lid by the cutting operation will fall into said adhesive and be held thereby against any possibility of escaping from said space.

In Figure 3 the top portion of the lid 25 in- 10 teriorly of the channel 20 is shaped to conform to the bottom 14 of the can. Otherwise the construction of the lid and the formation of the body 11 at the adjacent end is substantially the same 15 as described in connection with Figure 2, with the exception that the adhesive 24 is not shown within the space 23.

In order to properly guide the person opening the can, suitable indicia may be inscribed on the 20 bottom and top thereof such as the words "Open other end" on the bottom, and "Cut in channel" on the top.

In the two modifications thus far described the outer peripheral edge of the lid 18 formed by 25 the depending portion of the flange 21 is of greater diameter than the cylindrical wall of the body 10. In Figures 4 and 5 the lid 26 is made the same diameter as the body 11 with the result that the space 23 extending exteriorly about 30 the open end of the body will overlie the lowermost portion of the under layer 16. Otherwise the construction is practically the same as previously described. At the point where the flange 21 is turned inwardly and upwardly to provide the 35 portion 22, the material is rounded somewhat, instead of provided with rather a sharp angle as shown in Figures 2 and 3, so that said rounded portion will form, in combination with the similarly rounded adjacent portion of the wall 11, 40 a small groove 27 into which one of the jaws of an implement, such as a pair of pliers, may be inserted, the other jaw engaging the bottom of the channel 20. By compressing the handles of the implement 28 and utilizing the last-named 45 jaw as a fulcrum another means is afforded for removing the lid by withdrawing or pulling the portion 22 from the groove formed by the super- 50 posed layers 16.

It is obvious that the arrangements of the free 55 space as shown in Figs. 1, 2, 3, and 9, in which it is situated partly outside the vertical plane of the can body wall, will give to a pair of pincers or pliers, or to a so-called "Anchor" can opener, more chance to grip and permit more securely 60 the quicker withdrawal of the lid from the folds 16 and 31 respectively, than would be possible with the construction as shown in Figs. 4, 5, and 7, in which the outer wall of the free space is flush with or even inward from the vertical plane 65 of the can body wall 11.

In the embodiment of the invention shown in Figures 7 and 8 the cylindrical wall 11 of the can body is again turned inwardly and folded upon itself at 29 to form the rounded peripheral 65 edge of the open end of the said body to be closed by the lid 30. In this instance the superposed layers 31 of the fold in the material are somewhat longer than those previously described and are provided at a point more remote from the 70 extremity of the end of the body than are the layers 16. As a consequence an extension 32 of the body which actually forms the upper extremity thereof is left after the fold has been made and this extension is disposed vertically 75

and substantially parallel to the wall 11. The lid 30, which rests upon the rounded edge 29 of the body opening is provided with the annular channel 33 having, in this instance, a flat bottom 34. From this channel the material of the lid is folded upon itself as indicated at 35 to form the depending flange 36 having the inwardly and upwardly turned portion 37 which is insertable into the groove formed by the layers 31 and snugly engaged by the latter. In the fold 35 there is disposed a packing 38 which receives the upper extremity of the extension 32 and by utilizing suitable instruments, such as chucks disposed against the inner and outer walls of the fold 35, it will be apparent that pressure exerted upon said chucks toward each other will securely seal the extension 32 in said fold.

The bottom of the channel 34 combines with the upper layer 31 and with the extension 32 to form the space 39 which extends around the open end of the can body and in such relation thereto that when the blade of a can opener is made to penetrate the bottom of the channel 34 and is subsequently operated to cut around the lid, said blade will enter the space 39 and be prevented from puncturing the wall 11 of the can body by the double thickness of material formed by the upper layer 31 and portion 37 of the flange 36.

In Figure 9 the lid 40 again has a major portion of its top surface curved or convoluted, as in the other modifications previously described, so as to render it difficult for the user of the can to penetrate said top portion at a point within the confines of the constricted opening of the body. With the exception of the difference in the form of curve of the top portion of the lid 40 and the slight difference in the length of the fold formed in the wall 11 to provide the layers 31, the construction shown in Figure 9 is substantially the same as that described in connection with Figure 8, and therefore similar reference characters have been applied to both forms.

In the embodiment of the invention shown in Figure 10 the wall 11 is again folded upon itself as indicated at 41 and the portion of said wall extending from the uppermost fold is first rounded as indicated at 42 to reinforce this section of the wall. The extension 43 constituting the upper end of the wall projects upwardly from the rounded portion 42 and is then bent downwardly and outwardly upon itself to provide the depending flange 44. The lid 45 of the can body is once more provided with the guide channel 46 for receiving the can opener and the outer peripheral portion of said lid is then bent to provide a flange 47 which first extends downwardly and then upwardly into the groove formed by the extension 43 and flange 44. Suitable packing 48 is introduced between the inner wall of the channel 46, the extension 43 and the flanges 44 and 47, and by compressing these parts between two chucks engageable with said inner wall of the channel and the outer portion of the flange 47 the elements are brought securely into engagement and the can sealed at this point. Again as in the previous forms of the invention, a space

49 extending exteriorly of the open end of the body 11 is formed by the uppermost fold 41, the extension 43 of the body and the bottom of the channel 46, said space being penetrated by the blade of the can opener when it is forced through 5 the bottom of said channel prior to the cutting operation; and again as in the previous instances, at least one additional thickness of the material is interposed between the wall of the can body and the bottom of said channel so as to afford 10 protection against puncturing said wall by the can opener. In addition to the channel 46, in to which an opener may be inserted, there is also formed, by the extension 43, the depending flange 47 and the rounded part 42, another 15 channel for receiving the opener so that the can may be opened from the side instead of the top.

In the forms of the invention shown in Figures 7 to 10 inclusive the arrangement is such that the body of the can may be filled with its contents before the lid is sealed in position inasmuch as it is not necessary to compress together the superposed layers 31 and 41.

What is claimed is:

1. In a preserving can, consisting of three formed pieces, namely the can body, the bottom and the lid, the can body united with the lid by means of a fold and the latter made hermetical through a binder and through compression, the can body adjacent one end thereof inclined inwardly and upwardly and forming thereby conjointly with a part of the lid a free space and said free space locally separated from the space of the can that holds the contents thereof and said free space being of such depth and without 35 hindering objects as to allow a cutting tool to penetrate deep enough for permitting the severing of the outer walls of said free space and a guide channel on top of the can for guiding the cutting tool, and a material in said free space 40 having the quality to cause metal particles or filings dislodged at the opening of the can with a cutting tool to stick to it.

2. In a preserving can consisting of three formed pieces of the same material namely, the can body, the bottom and the lid, the can body united with the lid by means of a fold and the latter made hermetic through packing and through compression, the lid so shaped that a free space is obtained but locally separated from 50 the contents of the can, one wall of the part of the lid that limits said free space reaching inside of the vertical plane of the outer can body wall and inclined upwardly and inwardly, forming thereby the lower wall of said free space, and 55 said free space being annular and free from obstructing objects and of such depth and position as to permit a cutting tool to penetrate deep enough for severing the lid along said free space and thus preventing the falling of metal particles 60 into the contents of the can or the mixing of the latter with said metal particles at the removal of the lid and a guide channel on top of the can for guiding the cutting tool along said free space.

HEINRICH KARL.
